UNITED STATES PATENT OFFICE.

WILLIAM S. SCALES, OF SOMERVILLE, MASSACHUSETTS, ASSIGNOR TO THE
SYNCHRONOUS TIME COMPANY, OF PORTLAND, MAINE.

ELECTRIC REGULATING AND HAND-SETTING MECHANISM FOR CLOCKS.

SPECIFICATION forming part of Letters Patent No. 392,230, dated November 6, 1888.

Application filed November 18, 1887. Serial No. 255,484. (No model.)

To all whom it may concern:

Be it known that I, WILLIAM S. SCALES, of Somerville, county of Middlesex, State of Massachusetts, have invented an Improvement in 5 Synchronizing Mechanisms for Clocks, of which the following description, in connection with the accompanying drawings, is a specification, like letters on the drawings representing like parts.

- 10 This invention has for its object to construct a system for synchronizing clocks which is adapted for use upon district signaling-wires; and it consists in the combination, with an electric circuit containing several clocks, each 15 provided with a regulating device for the regulating member thereof, of a circuit-controlling device for rendering the said circuit operative to permit an impulse to be transmitted to the several clocks to be regulated, and to transmit the impulse, and a master-clock for effecting the operation of the said controlling device. The clocks, when included in district signaling or telephone lines, or in lines employed for other purposes than time, are normally cut out by means controlled by the train- 20 work of the clock, so that the transmission of signals or telephonic communications can have no effect upon the clock, the signaling-circuit being normally a closed circuit; and it being 25 desirable to have an open circuit for the transmission of the time-impulse, a circuit-controlling device is employed to open the line and thereafter transmit the time-impulse, the said circuit-controlling device being governed by 30 the master-clock.

The invention also consists in details of construction, to be hereinafter more fully pointed out.

- 35 Figure 1 shows in front elevation a portion 40 of a pendulum clock provided with controlling or regulating devices for the regulating member thereof, and also with hand-setting devices; Fig. 2, a detail showing the cut-out device of the clock, to be described; Fig. 3, a top view 45 of the clock shown in Fig. 1; and Fig. 4, a diagram of a circuit containing the clock to be regulated, the master-clock, and the circuit-controlling device operated by the master-clock.

Referring to Figs. 1, 2, and 3, the frame *a* is 50 of any suitable construction to support the usual train or wheel-work of a clock, the hand-arbor *a'* only of which is herein shown. A disk, *b*, is mounted to revolve frictionally upon the shaft or arbor *a'*, it having the usual sleeve 55 or hub carrying the minute-hand. The periphery of the disk *b* has a V-shaped notch, *b'*, which receives at stated times a pin, 2, attached to or projecting laterally from an ear, 3, secured to an arm or bar, *c*, fixed to a shaft, 60 *c'*, carrying the armature-bar *c''* of an electromagnet, *c'''*. The armature-bar *c''* is normally held retracted by gravity, and the pin 2 normally lies out of the path of movement of the disk *b*; but when said magnet is energized the 65 armature-bar, being attracted, throws the pin 2 into engagement with the disk, and if the said disk is not in its correct position at such time—namely, in a position whereby the pin 2 enters the deepest part of the notch without 70 moving the disk—then the pin will strike one or the other inclined side of the notch and thereby move the said disk. This forms essentially the hand-setting mechanism.

The arm or bar *c* has, preferably at its outer 75 end, an ear, *d*, provided with two pins, 4, one above the other, to receive between them the outer end of a lever, *e*, pivoted at *e'* to one arm, as *e''*, of a bell-crank lever, the other arm, *e'''*, of said bell-crank lever having a pin, 5, 80 which enters a slot or notch cut in one end of a pivoted regulating-lever, *t*. The lever *t* has two pins, 6, between which the usual pendulum, *p*, is suspended. The lever *e* near its outer end has an ear, 7, having a V-shaped 85 notch, and a stud or arm, 8, (see dotted lines, Figs. 1 and 2,) is fixed to the shaft *a'*, which, provided it be in true position, enters the notch of the ear 7 when the latter is depressed, it being understood that the said ear 7 and its 90 arm *e* are lowered with the bar *c*, being connected one with the other. When the ear 7 falls, if the regulating member *p* is vibrating correctly, the arm 8 will have arrived at such a position as to enter the deepest portion of 95 the notch of said ear without moving it; but if the clock has gained or lost ever so little, then the arm 8 will strike one or the other in-

clined side of the V-shaped notch of the ear 7 and move said ear and its arm e in one or the other direction longitudinally, thereby moving the bell-crank lever on its pivot e^6 and 5 raising or lowering the regulating-lever t to change the vibrating length of the pendulum.

The lever e and means for moving it and the lever t and its connections with the lever e represent one preferable form of regulating mechanism for the regulating member of the clock, which is governed as to its operation by the train of the clock; and I desire it to be understood that I do not limit myself to such form, as it may be modified in many particulars and 10 yet retain the essential feature of this invention—namely, controlling or regulating the relative movements of the pendulum by the clock-train.

It is designed to have the magnet effect the 20 operation of the controlling or regulating mechanism and hand-setting devices once each twelve hours, and to effect this result a master-clock is employed, and also a circuit-controlling device, to be described.

25 The master-clock (see Fig. 4) contains a scape-wheel, f , to the hub or shaft of which is attached an arm, f^2 , and also containing a pallet, f^3 , to which is attached a detent, f^3 , insulated from it. The outer end of the arm f^2 is 30 of sufficient width and is arranged to come beneath and to be struck by the detent f^3 twice every minute—viz., on two successive oscillations of the pendulum—and the said arm f^2 and the detent f^3 , being included in the local 35 circuit 20, operate to close the said circuit at such point twice each minute. The master-clock also contains a circuit-wheel, f^5 , adapted to rotate once an hour, and said circuit-wheel has an arm, f^6 , adapted to engage a contact-spring, f^7 , once during each revolution of the 40 wheel, and to remain in electrical engagement two minutes, so that during each hour the circuit 20 will be closed by the circuit-wheel f^5 two minutes, and during each minute will be 45 closed by the detent f^3 twice—viz., on two successive seconds—thereby effecting during each hour four impulses.

An electro-magnet, m , is included in the circuit 20, the armature m' of which is attached 50 to one end of a bent lever, n , pivoted at n' to a post or standard, the opposite end of said lever carrying a spring-controlled push-pawl, n^2 , to engage the teeth of a wheel, n^3 , fixed to a shaft, n^4 , having its bearings in suitable posts 55 or standards. A contact-arm, n^5 , is attached to the lever n , but insulated therefrom, and the co-operating contact-arm n^6 is fixed to the shaft n^4 . Another arm, n^7 , is fixed to the shaft n^4 , composed partly of conducting material 60 and partly of insulating material, and two contact-springs, n^8 n^9 , are attached to an insulating-block, n^{10} , said springs n^8 n^9 co-operating, respectively, with the insulating and conducting portions of the arm n^7 . The two contact-springs n^8 n^9 normally rest upon a platinum 65 block, n^{12} , and are included in a circuit, 50,

containing a battery, B , thereby maintaining said circuit normally closed. The said contact-springs n^8 n^9 are lifted at stated times by the arm n^7 from the block n^{12} , thereby opening the 70 circuit 50, and when lifted one of the springs, as n^8 , bears against a contact-point, n^{13} . The contact-point n^{13} and the contact-arm n^5 are included in a normally-open circuit, 60. The wheel n^3 has forty-eight teeth, and, as the magnet m is energized four times each hour, the 75 said wheel will be moved four teeth each hour, so that the shaft n^4 will make one complete revolution each twelve hours.

With the parts in the position shown in Fig. 80 4, the time has arrived for sending an impulse over the main circuit 50, and the operation of the parts is as follows: The circuit-wheel f^5 has just engaged its contact-spring f^7 , and while in such engagement the detent f^3 strikes the 85 arm f^2 twice successively during the first minute, thereby moving the wheel n^3 two teeth, causing the arm n^7 to lift the contact-springs n^8 n^9 from the block n^{12} , closing the spring n^8 against the contact-point n^{13} , so that the circuit 90 50 includes the spring n^8 , contact-point n^{13} , circuit 60, arm n^5 at one side, and the spring n^9 , arm n^7 , and shaft n^4 on the other side, and during the second minute the contact f^3 strikes the arm f^2 twice successively, again causing 95 the wheel n^3 to be moved two teeth, the movement of the said wheel caused by the first impulse of the second minute throwing the arm n^6 in contact with the arm n^5 , thereby closing the circuit 50, and the movement of the said 100 wheel caused by the second impulse of the second minute throwing the contact-arm n^6 beyond the arm n^5 , thereby breaking the circuit 60, which at this time is a part of the main circuit 50, and, as the said contact-arm n^6 passes 105 by the arm n^5 , the arm n^7 passes by the springs n^8 n^9 , permitting them to resume their normal position.

It will be seen that the circuit 50 has been 110 open for two minutes, or for more than one minute, and during said time an impulse has been transmitted, which energizes the magnet e^3 and effects the operation of the hand-setting mechanism and the controlling or regulating mechanism of the clock, or it may be several 115 clocks which are included in the circuit.

The circuit 50 is employed as a district-signaling circuit, and contains several signal-boxes, as D , and a receiving apparatus of any well-known description, as D' . To permit the 120 said signaling service to be effectually carried out and not affect the controlling-magnet e^3 of the several clocks, each clock is adapted to be cut out by its own train, the following-described mechanism being employed, viz: The 125 disk b is provided with an insulating-spot, 70, and a contact-spring, 75, pivoted to an insulating-block, 76, secured to the frame a of the clock, said spring bearing against the disk b , but normally lying out of path of the insulating-spot. Another contact-spring, 77, is attached to an insulating-block, 78, secured to 130

the frame, said spring bearing upon the arm *c*. The circuit 50 normally includes the spring 75, disk *b*, and spring 77, while the magnet *c'* is in a shunt, 52. A pin, 90, fixed to a wheel, 51, mounted loosely upon a shaft, *a'*, is adapted to make a complete revolution once in twelve hours, and said pin during said movement engages the outer end of the spring 75 and moves it upward or outward in position to bear upon 10 the insulated part of the disk *b* at the time that the impulse from the master-clock is being transmitted, to thereby include the magnet *c'* in the circuit to receive the said impulse, and when the impulse is transmitted, if the clock has 15 gained or lost, the disk *b* will not keep its correct position, so that the arm *e* when depressed will be moved in one or the other direction to thereby effect a change in the vibrating length of the pendulum. The insulated spot 70 is of 20 sufficient size to permit the spring 75 to bear upon it, say, two minutes or more, if desired, to include any ordinary irregularity in the clock. The spring 75 is provided with a projection, 79, which is struck by an ear, *d*, when 25 the latter is moved downward, to thereby move the spring back to its normal position, and to maintain the interruption of the circuit to keep the magnet *c'* included a sufficient length of time to accomplish its work the spring 77, 30 bearing upon the arm *e*, interrupts the circuit when the said arm is depressed.

I do not desire to limit myself to the particular construction of master-clock or of controlling devices herein shown, as it is obvious that the same may be made in various ways and yet accomplish the results herein specified.

I claim—

1. In a synchronizing mechanism for clocks, the regulating or controlling lever for the 40 regulating member of the clock and an operating bar or lever therefor, combined with an arm positively connected with and moved continuously by the clock-train for effecting the movement of said operating bar or lever, substantially as set forth.

2. In a synchronizing mechanism for clocks, the regulating or controlling device for the regulating member thereof, and means, as the arm *e*, for moving it, combined with an electrical device for moving the said arm *e* into engagement with a continuously-moving part of the clock-train by which it is moved, causing the regulating member of the clock to take a gaining or losing rate relative to its prior 55 performance, substantially as described.

3. In a synchronizing mechanism for clocks, the regulating device for the regulating member of the clock, the operating bar or lever for moving it when said bar or lever is thrown 60 into engagement with a continuously-moving

part of the clock-train, combined with the hand-setting mechanism, and the electrical device for throwing both the operating bar or lever employed for moving the regulating device and the hand-setting mechanism into 65 operative position, substantially as described.

4. In a synchronizing mechanism for clocks, the regulating mechanism for the regulating member of the clock, it consisting of the regulating-lever, the operating-lever therefor, and the continuously-moving part of the clock-train, and the electro-magnet for controlling the operation of said operating-lever, combined with an electric cut-out or switch continuously moved by the train of the clock for 75 automatically cutting the said electro-magnet into and out of circuit at stated times, substantially as described.

5. In a synchronizing mechanism for clocks, the regulating device for the regulating member, and the arm *e*, for moving it, combined with the arm *S*, directly connected with and forming a continuously-moving part of the train of the clock, with which the arm *e* co-operates, and with an electro-magnetic device 80 for throwing the arm *e* into engagement with the arm *S*, substantially as described.

6. In a synchronizing mechanism for clocks, the regulating device for the regulating member, the arm *e*, and the arm *S*, with which the 90 arm *e* co-operates, combined with the arm *e* and the disk or wheel *b*, with which it co-operates, substantially as described.

7. In a synchronizing mechanism for clocks, the regulating device for the regulating member, arm *e*, and arm *S*, combined with the arm *e*, and connecting means for connecting it with the arm *e* and the disk or wheel *b*, and the electro-magnet for moving the arm *e*, substantially 95 as described.

8. In a system of synchronizing clocks, the combination, substantially as described, of a normally-closed electric circuit containing several clocks, and mechanism normally cut out for moving the regulating members thereof, 105 that they may take a gaining or losing rate relative to their prior performance, a circuit-controlling device for opening the said circuit to introduce a master-clock, and also to transmit the time impulse, and the master-clock 110 which governs the operation of said circuit-controlling device, substantially as described.

In testimony whereof I have signed my name to this specification in the presence of two subscribing witnesses.
